Primary Examiner — Eric Goodman*Assistant Examiner* — Bao-Yen Nguyen(74) *Attorney, Agent, or Firm* — Symbus Law Group, LLC; Clifford D. Hyra(57) **CLAIM**

The ornamental design for a mounting device, as shown and described.

DESCRIPTION

FIG. 1 is a top view of a mounting device.

FIG. 2 is a bottom view of a mounting device.

FIG. 3 is a front view of a mounting device.

FIG. 4 is a rear view of a mounting device.

FIG. 5 is a perspective view of a mounting device showing the rear, right side, and top.

FIG. 6 is a perspective view of a mounting device showing the front, left side, and top.

FIG. 7 is a right side view of a mounting device; and,

FIG. 8 is a left side view of a mounting device.
